CLAIM

The ornamental design for a donut-warming lid for a coffee cup.

DESCRIPTION

FIG. 1 is a top perspective view of my new design for a donut-warming lid for a coffee cup, showing the item in use on a coffee cup;

FIG. 2 is a side elevational view thereof, it being understood that all side elevational views are identical;

FIG. 3 is a top plan view of the outside thereof;

FIG. 4 is a bottom plan view thereof;

FIG. 5 is a perspective view exposing the underside of the two-part design; and,

FIG. 6 is an exploded view thereof, showing the item in an opened condition of use.

The broken lines represent unclaimed environmental elements.
